(57) **CLAIM**

The ornamental design for an office adhesive tape for coating film transfer tool, as shown and described.

DESCRIPTION

FIG. 1 is a front view of an office adhesive tape for coating film transfer tool showing the claimed design;

FIG. 2 is a rear view thereof;

FIG. 3 is a bottom plan view thereof;

FIG. 4 is an enlarged view of a portion thereof taken from detail 4 shown in FIG. 1;

FIG. 5 is a front elevation view of the office adhesive tape for coating film transfer tool, with the coating film transfer tool in use; and,

FIG. 6 is an enlarged view of a portion thereof taken from detail 6 shown in FIG. 1.

The dash-dash broken lines in the drawings represent portions of the office adhesive tape for coating film transfer tool that form no part of the claimed design. The dash-dot-dash broken lines in the drawings represent the bounds of the enlarged views and form no part of the claimed design. In FIG. 5, the coating film transfer tool is shown in dash-dash broken lines and represents environmental subject matter and forms no part of the claimed design.
